UNITED STATES PATENT OFFICE

WILLIAM RALEIGH KERR GANDELL, OF LONDON, ENGLAND

SUITCASE

Application filed July 14, 1927, Serial No. 205,732, and in Great Britain July 14, 1926.

This invention relates to suit cases of the kind comprising a lower box-shaped member open at the top and an upper lid member adapted to fit over the upper portion of the lower member in the manner of the lid of an ordinary cardboard box, the cubic space available for the transport and storage of articles being regulated or varied at will.

According to this invention in order that the upper and lower members may be firmly secured together at various heights, the upper member is provided with one or more locking members or bolts adapted to engage with any one of a plurality of superposed slots or openings in lock-receiving members secured to the lower member. Such locks and lock-receiving members are preferably duplicated on two opposite sides or ends of a suit case.

When, however, it is desired to pack additional articles in the suit case, these are stored in the upper or lid member. In this case the lid obviously cannot be pressed down tightly on to the upper edges of the lower member, but only a certain distance until the articles in the lid member come into contact with the articles in the lower or box member, such distance depending upon the depth of the articles in the lid member. If a horizontal partition be employed, this will serve to separate the articles in the upper member from those in the lower member.

The lid member is provided with tapes or other devices for retaining articles within the lid member. Also, the lower member may be provided with one or more horizontal and/or vertical partitions to prevent crushing of the articles.

One of such horizontal partitions is in the form of a substantially rigid plate of not less than the size of the outside measurements of the top of the lower member, and may be notched to enable it to be held under the tapes on the inside of the upper member. This partition does not enter the lower member, but rests on the upper edges of it, and prevents articles in the upper member from exerting pressure on those in the lower member.

In order that the suit case or the like may be properly balanced when carried, inde-

pendently of the extent to which it may have been extended, a handle may be arranged so that it may be caused to slide transversely. In this way such handle may be positioned centrally relatively to the height or depth of the suit case.

The handle may be permanently attached at one end to the lower member and detachably secured at its other end to the upper member, or the handle may be provided with two gripping members in the manner of a kit bag, one of these gripping members being secured to the upper and one to the lower member.

The lid member may be provided with any number of handles wherever convenient.

In addition to the two locks described, one or more additional spring catches may be provided, which would engage in suitable lock-receiving members with a plurality of slots or holes one above another in or on the lower member.

Among other purposes to which this invention may be applied is that of luggage carriers for motor road vehicles. Such carriers may serve to contain one or more suit cases or the actual articles for personal use themselves.

The invention is illustrated in the annexed drawings in which—

Fig. 1 is a front elevation of a suit case;

Fig. 2 is a plan view;

Fig. 3 is a side elevation, and

Fig. 4 is a section on the line 4—4 of Fig. 3.

In these drawings, *a* represents the upper or lid member and *b* the lower member.

For packing purposes the two members *a* and *b* are entirely independent of one another, and may be removed one from the other in the manner of a cardboard box, the upper member *a* being inverted during the packing process. When all the requisite articles can be packed in the lower member *b* the underside of the upper member *a* lies flush with the upper surface of the lower member *b* or if, as shown in the drawings, a horizontal partition *x* is employed, the under surface of the member *a* rests on this partition.

Means are provided whereby the member *a* may be retained at various levels relatively to the member *b*. These means consists of a plurality of co-operating locks or bolts *c* and 5 lock-receiving members *d*. The latter comprise a plurality of slots *e* adapted to receive the catch member of the lock. A pair of these retaining devices is preferably employed, one at each end of the suit case.

10 In addition to these locks additional spring catches *f* are employed, one being arranged at each side of the suit case.

The members *f* are adapted to engage any one of a plurality of superposed slots *g*.

15 The lower member is provided with horizontal partitions *h*, of which three are shown, although any desired number may be employed. These partitions are on one side fitted into grooves *j* whilst on the other side

20 they rest upon ledges *k*, suitable clips *l* being provided to hold them in place. These partitions *h* which are interchangeable may be removed and arranged vertically, gaps *m* in the ledges being left for this purpose.

25 The partitions may, if desired, be hinged together in a permanent manner. Straps or tapes *n* may be provided to assist in retaining articles in position. A handle *o* of ordinary type may conveniently be provided on 30 the upper surface of the member *a* as shown.

As an addition or alternative to the handle *o* a further handle *p* adjustable as to its position may be employed. This latter handle, as shown in Figs. 1 and 2, is secured to one side 35 of the member *a*, and its position may be adjusted by means of two spring catch members adapted to engage any pair of superposed slots *q*.

Articles stored in the upper member *a* are 40 held in place by means of the partition *x*, which is formed with notches *r* by means of which it is held beneath tapes *s* on the member *a*. The partition *x* is of the same size as the outside of the member *b*, and rests upon 45 the upper surface of the latter, so that articles in the member *a* exert no appreciable pressure on those in the member *b*.

Two holes *x'* are formed in the partition. These allow of the insertion of two fingers 50 when it is desired to remove the partition.

In order that the hasp of a bolt or lock may bear evenly on the lid member of the suit-case packing pieces of about the thickness of the frame may be secured to the outside of 55 the lid member or to the inside or to both sides.

The substantially rigid partition *x* may be made with projecting edges or flanges to fit over or into the lower member like a lid.

60 Having thus described the nature of my said invention and the best means I know of carrying the same into practical effect, I claim:—

1. A suit case comprising a lower member 65 having a bottom and side and end walls ex-

tending upwardly from said bottom; an upper member comprising a top and side and end walls depending from said top, the side and end walls of said upper member being adapted telescopically to receive the side and end walls of the lower member, partitions each of a width not greater than the depth of said lower member and insertable in said lower member, and means carried by said lower member for supporting said partitions in either horizontal or vertical position.

2. A suit case comprising a lower member having a bottom and side and end walls extending upwardly from said bottom; an upper member comprising a top and side and end walls depending from said top, the side and end walls of said upper member being adapted telescopically to receive the side and end walls of the lower member, a longitudinally grooved bar and a ledge projecting, respectively, from the inner sides of the side walls of said lower member, said bar and ledge having aligned transverse slots, and partition members each of a width not greater than the depth of said lower member and insertable in said lower member in a horizontal position with one of their ends in the groove of said bar and their opposite ends supported by said ledge or in vertical positions with their opposite ends in the transverse grooves of said bar and ledge.

3. A suit case comprising a lower member having a bottom and side and end walls extending upwardly from said bottom; an upper member comprising a top and side and end walls depending from said top, the side and end walls of said upper member being adapted to receive telescopically the side and end walls of the lower member, a longitudinally grooved bar and a ledge projecting, respectively, from the inner sides of the side walls of the lower member, and a partition insertable in said lower member and with one edge in the groove of said bar and resting at its opposite edge on said ledge, and a removable substantially rigid partition, the length and breadth of which is not less than the external length and breadth of the lower member which rests upon the upper edges of said lower member when the case is closed, for the purpose specified.

In testimony whereof I have signed my name to this specification.

WILLIAM RALEIGH KERR GANDELL.
